UNITED STATES PATENT OFFICE.

GEORGE PAYNE AND JOHN ROSS OF ORILLIA, ONTARIO, CANADA.

WATER-HYDRANT.

No. 909,327.

Specification of Letters Patent.

Patented Jan. 12, 1909.

Application filed December 13, 1907. Serial No. 406,373.

To all whom it may concern:

Be it known that we, GEORGE PAYNE and JOHN Ross, both of the town of Orillia, in the county of Simcoe, in the Province of Ontario, 5 Canada, have invented certain new and useful Improvements in Water-Hydrants, of which the following is the specification.

Our invention relates to improvements in water hydrants, and the object of the invention is to devise a hydrant for lawn and house use, which will not be liable to freeze and which will be simple, positive and effectual in operation and it consists essentially of a casting having the inlet at one side 10 at the bottom and the outlet extending upwardly at one side from the top, tapered seats located in the valve one above the other and a valve stem in two portions having tapered valves constructed as hereinafter 15 more particularly explained.

The invention is shown in the accompanying drawings, in which—

Figure 1 is a vertical section through the improved hydrant and Fig. 2 is a central 25 cross section thereof.

A is the body casting, which has a tapered seat A¹ at its upper end for the upper leather stop valve B. The body casting A is provided with an internal thread A² at its lower 30 end to receive the nipple A³ in which is formed the tapered seat B¹.

C is the reducing elbow, which is screwed on to the nipple A³ and is provided with an internally threaded outer end C¹.

D is the upper end of the valve stem, which is provided with an enlarged lower portion D¹ hollow and provided with an internal thread D². The upper end of the valve stem B is provided with a thread D³ 35 and reducing terminal taper D⁴ preferably square in cross section. The tapered valve B fits between the shoulder D⁵ formed by the enlarged lower portion D¹, and the nut E screwed on to the threaded portion D³ of the 40 valve stem D.

The thread D² is a quick acting pitched thread for receiving the male thread F¹ formed at the upper end of the stem F, which is provided with wings F² fitting in 45 recesses A⁵, formed in the side walls of the orifice A⁴, and extending above the tapered valve seat in the nipple A³. The wings allow of a sliding but a non-rotating connection between the valve stem and the nipple A³.

The wings also form shoulders F³ against 55 which abuts the lower tapered valve G.

H is a washer and I is a nut, whereby the lower tapered valve is held in position.

The body casting A is formed with a branch outlet A⁶ provided with an internal thread as 60 indicated. It is to be understood that the stems D and F are provided with a right hand thread and the operating end of the stem D is given a left hand motion and by being given a left hand motion will cause the stem F to 65 recede from the stem D and open the lower valve G, thus letting the inlet water find an entrance through the nipple A³, by means of the opening therein. If the valve mechanism is now closed again until the lower valve G is 70 seated no more water will be admitted. Upon a still further right hand turning of the stem D the upper valve A¹ will be caused to descend and allow all the entrapped water above the lower valve to escape as will be 75 readily understood. It will thus be seen that a means is afforded of getting rid of the standing water in the spout pipe connected to the branch outlet A⁶. The tapered portion D⁴ is for the purpose of receiving the usual key 80 socket for manipulating the valve.

Such a hydrant as we describe is simple, readily operated and not liable to get out of order, and effectually disposes of the liability 85 of the water freezing in the hydrant, which is the important desideratum we have attained in our invention.

What we claim as our invention is:

In a hydrant, the combination with a body casting having a branch outlet at the top 90 extending vertically upward on one side of the center of the casting and a center opening extending through the center of the top of the casting and flaring outwardly and downwardly, of a nipple secured into the 95 bottom of the casting provided with a central tapered valve seat having a central orifice extending from the top of the seat to the top of the nipple, vertical recesses formed in the sides of the orifice, an elbow screwed on 100 the nipple, a two-part valve stem having an enlargement therein provided with an interiorly threaded portion and a tapered valve secured on the upper member of the stem above such enlargement and fitting 105 within the central opening of the casting, a nut secured on the upper valve stem above the valve, such valve stem terminating in a

squared tapered end, a quick pitch thread formed on the lower member of the two-part valve stem and fitting at the top within the internally threaded portion of the enlargement of the upper valve stem, radial wings extending from the lower stem member and designed to fit within the recesses formed in the sides of the orifice of the nipple, a tapered valve fitting against the wings and

designed to seat itself within the tapered 10 seat of the nipple, and a nut and washer for holding the lower tapered valve in position.

GEO. PAYNE.
JOHN ROSS.
